UNITED STATES PATENT OFFICE.

CHARLES FRITZ, OF CHICAGO, ILLINOIS.

DRAIN CLEANER.

Application filed January 2, 1920. Serial No. 348,849.

To all whom it may concern:

Be it known that I, CHARLES FRITZ, a citizen of the United States, and a resident of the city of Chicago, county of Cook, and 5 State of Illinois, have invented certain new and useful Improvements in Drain Cleaners, of which the following is a specification.

My invention relates to new and useful improvements in drain cleaners, and has for its 10 object the provision of a drain cleaner which will be simple in structure, economical of manufacture, and highly efficient in use.

Another object is the provision in a drain cleaner of means for removing the material 15 loosened by the cleaner.

Other objects will appear hereinafter.

The invention consists in the combinations and arrangement of parts hereinafter described and claimed.

20 The invention will be best understood by reference to the accompanying drawings forming a part of this specification, and in which,

Fig. 1 is a side elevational view of my invention,

Fig. 2 is a rear elevational view of my invention, and

Fig. 3 is a fragmentary sectional view of my invention.

30 My invention is designed primarily for use in removing foreign substances from a drain pipe which are accustomed to lodge therein and clog the same.

The approved form of construction comprises a stem 6 formed on one end of which 35 is a shaft 7. Rotatably mounted upon the shaft 7 is a hub 8 which is retained in position by means of a washer 9 and pins 10 which project through the shaft 7. Projecting outwardly and inclined downwardly in

40 a spiral manner are blades 11 which converge to and are joined together at a point 12. Mounted upon one side of the blades 11 are posts 13 which are inclined upwardly relatively to the blades 11 and are diagonally cut at their ends 14 so as to present a surface which lies in a vertical plane parallel with the vertical plane of the axis of the hub. The member 6 is provided with openings 15 through which bolts may be projected for the purpose of securing to the member 6 a flexible handle 16.

50 In use, the blades which are provided with diagonally cut edges are inserted into the drain pipe, the operator retaining hold of

the handle 16. As the blades pass through material or liquid in the drain pipe, the blades are caused to rotate, owing to their spiral form. In rotating, the cutting edges serve to cut the material which is clogged 60 in the drain pipe and loosen the same. The point 12 first enters the material and the blades 11 are rendered more effective because of the converging arrangement. When the material which is clogging the drain pipe 65 has been loosened by the blade, the same, with the use of drain cleaners heretofore constructed is allowed to remain in the drain pipe and is flushed through the drain pipe. When this material has accumulated in very 70 large quantities, it may again gather in large quantities and clog the drain pipe farther on, thereby rendering its removal much more difficult. By obviating this difficulty, I have provided laterally projecting 75 and upwardly inclined posts 12, which engage the loosened material and prevent its passage further into the pipe. When the material has been loosened in sufficient quantities, the drain cleaner is removed and with 80 it the loosened material, inasmuch as the same clings to the posts 13.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations 85 and modifications as come within the scope of the appended claims.

Having described my invention, what I claim as new and desire to secure by Letters Patent is—

1. A drain cleaner comprising a shaft; a hub rotatably mounted on said shaft; and cutting blades formed integral with said hub, curving outwardly therefrom and joined together at an outward point, said 100 blades and hub rotating automatically when said cleaner is thrust in the drain pipe, substantially as described.

2. A drain cleaner comprising a hub; cutting blades formed integral with said hub 105 and inclined outwardly and downwardly, spirally from said hub; and posts mounted on and inclined upwardly relatively to said blades for engaging and retaining material loosened by said blades, the surfaces of the 110

ends of said posts lying in a plane parallel with the axis of said hub, substantially as described.

3. A drain cleaner comprising a hub; a shaft rotatably mounted in said hub; a flat bar integral with said shaft and having openings for bolting a handle thereto; pointed cutting blades formed integral with said hub and inclined outwardly and downwardly, spirally from said hub and joined at their points; and means mounted on said blades for engaging and retaining material loosened by said blades, substantially as described.
- 10 4. A drain cleaner comprising a hub; a

shaft rotatably mounted in said hub; cutting blades inclined outwardly and downwardly, spirally from said hub, converging to a point at their lower ends; and posts mounted on said blades for engaging and retaining material loosened by said blades, substantially as described. 20

In testimony whereof I have signed my name to this specification in the presence of two subscribing witnesses.

CHARLES FRITZ.
